ATTORNEYS

has three stitches 29, 30, 31 and 32, 33, 34 on each outermost edge 21 and 22 respectively to correspond to the three pleats 23, 24, 25, and 26, 27, 28 respectively thereof.

From this construction, it is also apparent that a portion of the outermost end 21 and 22 is folded over an adjacent portion 21a and 22a respectively a predetermined distance to conveniently fabricate the desired number of pleats on each of the opposite outermost edges.

The entire length of fabric material is then subjected to a specially adapted sewing machine such as a Wilcox-Gibson machine which is provided with a pleating attachment specially devised for the novel operation of pleating the curtain fabric as hereinabove described. The pleating attachment is essentially constructed of a durable metal and is provided with a plurality of structural features adapted to form a plurality of folds in a fabric material during the pleating and stitching operations.

The continuous length of a curtain fabric material or roll may be subjected to mass production processes suitable for large scale manufacturing wherein the pleats are stitched continuously at high speed without interruption or they may be novelly ornamented individually as custom made curtain fabrics for particular window lengths, room furnishings, etc.

Some of the most salient features of the present invention reside in the simplicity of construction with a resulting negligible increase in manufacturing costs as well as providing a readily adaptable decorative arrangement for interior decorators.

It will be understood further that the invention is not limited to the exact disclosure herein described but may lend itself to a variety of expressions within the scope of the appended claim.

5 What is claimed is:

A curtain fabric having at least one pleated edge portion, said edge portion having three parallel pleats of equal size, one of said pleats being located upon the edge of said edge portion, the distance of said one pleat from another pleat being equal to the distance between said other pleat and the third pleat, said edge portion further having an underlying piece of fabric extending between said edge and the third pleat and including a folded portion located directly below said third pleat and being of the same size as said third pleat; and three lines of stitching extending parallel to each other and said edge, one of said lines of stitching joining said one pleat with said underlying piece of fabric, the other one of said lines of stitching joining said other pleat with said underlying piece of fabric, and the third one of said lines of stitching joining said third pleat with said underlying piece of fabric and with said folded portion.
